MONITORING DEVICE FOR TELEVISION SYSTEMS

Thomas T. Goldsmith, Jr., Cedar Grove, N. J., assignor to Allen B. Du Mont Laboratories, Inc., Passaic, N. J., a corporation of Delaware

Original application June 21, 1941, Serial No. 399,055. Divided and this application August 5, 1943, Serial No. 497,455.

2 Claims. (Cl. 178—7.5)

This invention relates to a device for monitoring received television signals. In carrying out the invention a cathode-ray tube is provided for receiving a television picture signal and a vacuum tube is connected in parallel therewith so that a composite mixture of the incoming picture signal and a local blanking signal can be monitored on an oscillosograph.

This is a division of my application Serial No. 399,055, filed June 21, 1941, now Patent No. 2,373,114, granted April 10, 1945.

The invention may be understood from the description in connection with the accompanying drawing, which shows how various units may be connected and is in part a diagram of connections illustrating how the invention may be practiced.

In the drawing, reference character 1 indicates a television receiver for an input signal through connection 2 either to a transmission line or through the air. The receiver delivers a composite television signal 3 that is delivered to a one-stage amplifier 4 which inverts the picture signal. This inverted signal is passed through a direct current inserter 5, to be described in detail later, which controls the reference level from which the modulation occurs and yields a wave form which is opposite in polarity to the conventional wave form 3. This latter wave form is delivered by means of connection 7 to the grid 48 of the bright cathode-ray tube 8, thus providing the grid modulation to this tube 8 for producing a bright reversed polarity television picture on the screen of this tube.

The television receiver 1 delivers a horizontal sawtooth wave form by means of connection 11 to a horizontal deflection plate of cathode-ray tube 8 and to the horizontal blanking generator 12. The receiver 1 also delivers a vertical sawtooth wave form by means of connection 13 to the tube 8, and to the vertical blanking generator 14. The horizontal blanking generator 12 and the vertical blanking generator 14 may consist, for example, of circuits of the type described in the Campbell Patent 2,207,048.

The square wave form blanking pulses from generators 12 and 14 are suitably mixed in the blanking mixer 17 and after passage through a direct current inserter 25 the blanking signals are applied by means of connection 26 to the cathode 47 of the cathode-ray tube 8.

As described in the parent application, the composite television picture signal in negative or reversed polarity is applied to lead 40 and is

passed through the condenser 41 to a diode tube 42 which is so connected as to provide direct current insertion to control the pedestal level of the television picture signal at a fixed voltage relation for the grid 48 of the cathode-ray tube 8. The resistor 44 between tube 42 and lead 7 is of low resistance value, yet sufficiently high in resistance so that the synchronizing peaks on the composite wave form are practically ignored; consequently the signal appears on the plate 43 of the diode 42 as though the pedestal level were essentially flat from the beginning to the end of the blanking interval. A high resistance leak 45 is placed across the diode 42 so that the voltages may return to normal after momentary unusual surges. The condenser 41 tends to apply signals to the plate 43 which go positive and negative with respect to a predetermined voltage. However, upon an attempt to drive the plate 43 positive with respect to the cathode 46, the tube 42 will conduct current and establish a bias voltage on the condenser 41 so that no subsequent signals can go more positive than the cathode 46. The reference voltage level is established in this way, and the television signals are maintained always negative, except for the synchronizing peaks, and the pedestal level is caused to assume a fixed voltage to maintain the proper brilliance setting of the grid 48 in the cathode-ray tube 8. In this way the receiver automatically varies the absolute brilliance of the received picture when the transmitter sends one line, for example, which is essentially bright on a standard picture of positive polarity and a subsequent line which is essentially dark in a standard picture of positive polarity.

It is to be remembered that the cathode-ray tube 8 reproduces the television picture in negative polarity and therefore this direct current inserting diode 42 accomplishes the result of maintaining a direct current level for maximum white with means for modulating always toward black from this level, whereas the conventional tube with a picture of positive polarity has a direct current inserter for maintaining a constant black level with facilities for modulating toward the white.

The connector 49 carries the locally generated blanking signals from the blanking mixer 17 and introduces these signals through the coupling condenser 51 to the cathode 52 of the direct current insertion diode 53. The plate 54 of this diode is connected to a positive bias voltage supply by means of the potentiometer 57. The condenser

15 is employed to prevent blanking signal voltage from appearing across the potentiometer 51. The high resistance 56 shunts the diode and enables the circuit to return to its operating range automatically after an abnormal surge may have appeared. By means of the potentiometer 51 the absolute value of the direct current voltage may be set independent of incoming signals and this potentiometer serves as the brightness control of the cathode-ray tube 8. The vacuum tube 58 is connected as a cathode follower stage to pass the blanking signals without inversion of polarity but with reduction of source impedance. The blanking signals are applied from the direct current inserting diode 53 to the grid 59 of this tube. The cathode 60 is connected directly to the cathode 47 of the cathode-ray tube 8. The resistance 61 in the cathode circuit of tube 58 is of low value so as to transmit the blanking wave forms without distortion and so that changes in current in the cathode-ray tube 8 will not cause an appreciable change in the direct current level control circuit.

A vacuum tube 70 is connected in parallel with the cathode-ray tube 8 for the purpose of providing monitoring of the combination signal resulting from the two signals applied, respectively, to the cathode 47 and the grid 48 of the cathode-ray tube 8. The combination signal appears on the cathode-ray tube screen of tube 8 as changes in brilliance, but for adequate control of these signals it is desirable to produce and monitor the resulting wave form of the combination. Therefore the grid 71 of vacuum tube 70 is connected directly to the grid 48 of the cathode-ray tube 8. The cathode 72 of tube 70 is connected directly

5 to the cathode 47 of tube 8. The plate 73 of tube 70 thus carries a current which is characteristic of both of the signals that are applied to tube 8. A voltage develops across the plate load resistor 14 which represents this combined signal. It may be applied by means of a selector switch 76 to the vertical deflection system V or y-axis terminals of the oscilloscope 78 while a sawtooth wave of proper frequency is applied to the H or x-axis terminals in the usual way so that the wave form will appear on the screen 79 of the oscilloscope for monitoring purposes. The selector switch 76 also provides for monitoring the signal through the connection 88 that appears upon the cathodes 47 and 72 of tubes 8 and 70 and for monitoring the signal through the connection 81 that appears upon the grids 48 and 71 of these tubes, thus providing monitoring of any one of these signals independently. The switch 76 may 10 also be used to monitor other points in the circuit if desired by use of the lead 82.

What is claimed is:

1. In a television system, a cathode-ray tube and a vacuum tube, means to apply a television picture signal to the control grids of each of said tubes, means to apply blanking signals to the cathodes of said tubes, and means for monitoring a composite mixture of said signals.

2. In a television system, a cathode-ray tube and a vacuum tube, means to apply a television picture signal to the control grids of each of said tubes, means to apply blanking signals to the cathodes of said tubes, and an oscilloscope for monitoring a composite mixture of said signals.
